UNITED STATES PATENT OFFICE

WILLIAM L. CONRAD, OF BOSTON, MASSACHUSETTS

PROCESSING APPARATUS

Application filed August 2, 1928. Serial No. 296,945.

This invention relates to processing apparatus.

Processing apparatus in which textile material is subjected to a process involving the use of a treating liquor has many applications, such as boiling, dyeing, chemicing, bleaching, etc.

The apparatus embodying the invention is designed to carry on a process continuously and to operate on a web or rope of fabric or on connected skeins of yarn or like material which is continuously fed into the apparatus in which liquid is circulated and continuously withdrawn therefrom. The apparatus is so constructed and arranged as to accumulate enough of the fabric between the entering and leaving points to allow the fabric to be subjected to the action of the liquor for a sufficient length of time for the liquor to have the desired action on the fabric.

This invention more particularly relates to means in apparatus of the character specified for supporting the material.

The invention has for its salient object to provide supporting means for the material in a boiling or bleaching vat or keir so constructed and arranged that the depth to which the material is submerged can be regulated and the withdrawal of the material from the support can be controlled.

Further objects of the invention will appear from the following specification taken in connection with the drawings, which form a part of this application, and in which

Fig. 1 is a sectional elevation of apparatus constructed in accordance with the invention;

Fig. 2 is a detail sectional elevation taken substantially on line 2--2 of Fig. 1; and

Fig. 3 is a sectional elevation showing a slightly different form of supporting shelf constructed in accordance with the invention.

The invention briefly described consists of a vat or keir having means for feeding textile material thereto and having supporting means therein for supporting the material in the vat. The supporting means is so constructed and arranged that it can be bodily, vertically adjusted and, furthermore, is so constructed and arranged that it can be angularly adjusted. The vertical adjustment

permits the supporting of the material at different depths in the vat and the angular adjustment is provided for the purpose of facilitating or retarding the withdrawal of the material from the supporting means. Also, if desired, the supporting means can be dropped vertically out of supporting position. Furthermore, the invention includes shelves fixedly supported in a vat and extending toward each other, the inner ends of the shelves being spaced apart.

Further details of the invention will appear from the following description.

The supporting means is adapted for use in any desired form of keir or vat but in the form of the invention illustrated there is shown a keir similar to that disclosed in Patent No. 1,665,624. In the form of the apparatus illustrated in the drawings, there is shown a receptacle or keir 10 provided with a fabric containing portion 11 separated from the remaining portion of the receptacle by a downwardly extending partition 12. The partition 12 and the opposite side wall 13 of the receptacle are provided with pairs of inwardly extending flanges 14 and 15 having alined perforations 16 and 17.

Each flange has bolted thereto, by means of bolts 20, a bracket 21, the bracket being vertically adjustable on the flange since the bolts 20 can be secured through any desired openings 16 or 17 in the flanges.

The brackets on the flanges of each pair are vertically adjusted to the same height and each bracket has pivoted thereon at 25, a shelf 26, the shelf extending between the two brackets. In the form of the invention shown in Fig. 1, each shelf has mounted thereon rollers 28 on which the material rests.

Each bracket 21 has formed therein a series of perforations 30 and a pin 31 can be inserted in any desired perforation to support the shelf 26. It will be understood that the pins in both brackets of each pair of brackets will be positioned at the same level.

It will be obvious that the brackets and shelves carried thereby can be positioned at any desired height, thus determining the depth to which the material is submerged in the treating liquor. Furthermore, the shelves

can be adjusted on the brackets to the desired inclination, thus facilitating or retarding the withdrawal of the bottom layer from the supporting material.

5 Any desired means may be provided for feeding the material into the vat or keir. In the form of the invention shown, the feeding and guiding mechanism is supported on a pair of rails 35 and 36 mounted on the top 10 of the keir and extending longitudinally thereof. A carriage 37 is provided with rollers 38 and 39 which are mounted on the tracks 35 and 36. The carriage can, if desired, be fed back and forth on the tracks in the manner shown in Patent No. 1,665,624.

15 The carriage 37 has a funnel shaped mouth or opening 40 adapted to receive and guide the fabric to feed rolls 41 and 42 and the roll 41 is mounted on a shaft 43 which can be 20 driven from any suitable source of power and the roll 42 is driven by frictional engagement with the roll 41 and is freely rotatable on a shaft 45. The roll 42 has eccentrically secured thereto a pitman 47 which is connected at its opposite end to a crank 48 carried by a pivot shaft 49 on which is mounted a 25 feed tube 50. The upper end of the tube 50 is disposed below the feed rolls 41 and 42 in a position to receive the material as it is 30 fed downwardly by the feed rolls.

35 In order to insure the thorough permeation of the material with the treating liquor, means is provided for spraying the liquor on the material as it is fed downwardly from the feed rolls and before it is piled in zigzag folds across the receptacle or is submerged in the bath of liquor. This is accomplished by means of a pump 60 which is adapted to continuously withdraw liquor from the bottom 40 of the receptacle and feed the liquor upwardly through a conduit 61 to pipes 62, 63, 64 and 65, which extend around the four sides of the top of the receptacle. These pipes are provided with openings therein 45 adapted to direct the liquor downwardly as shown in Fig. 1 so that it will impinge against and thoroughly permeate the fabric as the fabric is fed downwardly by the feed rollers and is guided back and forth across the 50 receptacle by the pivoted sleeve 50.

An overflow pipe 70 is connected to the receptacle 10 and is adapted to conduct the liquor downwardly into the bottom of the receptacle through conduits 71 and 72.

55 The fabric is led from the bottom layer supported on the shelves around idler rolls or guide rods 75 through an opening 76 in a bracket 77 and through squeeze rolls or wringer rolls 78 which squeeze out excess 60 liquor from the fabric.

In the form of the invention illustrated in Fig. 3, the shelf consists of a flat plate 80 which is pivoted to the two brackets of the pair of brackets and has a downwardly 65 curved outer end 81. The plate may be

formed of any desired material, such as metal or wood.

From the foregoing description it will be seen that the supporting shelves for the material in the keir or vat can be bodily adjusted vertically, it being understood that both shelves will be supported at the same height. Thus the material can be submerged to the desired depth in the keir. Furthermore, the shelves can be pivotally adjusted to the desired inclination so as to facilitate the removal of the bottom layer of material as the material is fed out of the keir or vat by the feed rolls 78. When the material is heavy and the weight of the material on the shelves tends to unduly retard the withdrawal thereof, the shelves can be inclined downwardly. On the other hand, with light materials it may be desirable to adjust the shelves to the horizontal position shown in Fig. 1.

80 Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

85 What I claim is:

1. Apparatus of the character described comprising a receptacle, means for feeding material into said receptacle, and means for supporting the material in the receptacle, said supporting means being pivotally and bodily adjustable in said receptacle.
2. Apparatus of the character described comprising a receptacle, means for feeding material into said receptacle, and means for supporting the material in the receptacle, means for withdrawing the material from the bottom layer in the receptacle, said supporting means being angularly adjustable and vertically adjustable.
3. Apparatus of the character described comprising a receptacle, means for feeding material into the receptacle, and means including shelves on opposite sides of the receptacle for supporting the material in the receptacle, said shelves having rollers mounted thereon.
4. Apparatus of the character described comprising a receptacle, means for feeding material into the receptacle, and means including angularly adjustable shelves for supporting the material in the receptacle, said shelves having rollers mounted thereon.
5. Apparatus of the character described comprising a receptacle, means for feeding material into the receptacle, and means including vertically and angularly adjustable shelves for supporting the material in the receptacle, said shelves having rollers mounted thereon.
6. Apparatus of the character described

comprising a receptacle, means for feeding material into the receptacle, and means including shelves for supporting the material in the receptacle, said shelves having rollers mounted thereon and being bodily, vertically adjustable in the receptacle.

7. Apparatus of the character described comprising a receptacle, means for withdrawing material from the receptacle, and means in the receptacle intermediate the receiving and delivery ends thereof for supporting the material, said means including shelves supported in the receptacle and extending toward each other but spaced apart at their inner edges.

8. Apparatus of the character described comprising a receptacle, means for withdrawing material from the receptacle, and means in the receptacle intermediate the receiving and delivery ends thereof for supporting the material, said means including pivoted shelves supported in the receptacle and extending toward each other but spaced apart at their inner edges.

25 9. Apparatus of the character described comprising a receptacle, means for withdrawing material from the receptacle, and means in the receptacle intermediate the receiving and delivery ends thereof for supporting the material, said means including shelves mounted on substantially horizontal pivots and movable from nonsupporting vertical position to substantially horizontal supporting position, and means for supporting said shelves in a plurality of positions of adjustment.

In witness whereof, I have hereunto set my hand this 31st day of July, 1928.

WILLIAM L. CONRAD.
